TABLE OR SIMILAR ARTICLE

Florence S. Knoll, New York, N.Y., assignor, by mesne assignments, to FSB Corp., a corporation of New York

Filed Nov. 25, 1957, Ser. No. 48,646

Term of patent 14 years

(Cl. D33—14)

Fig. 1.

Fig. 2.

Fig. 3.

Fig. 1 is a perspective view of a table embodying the new design;

Fig. 2 is a plan view of the table of Fig. 1, taken on a reduced scale; and

Fig. 3 is a side elevation view of the table of Fig. 2.

The design is characterized by a recess provided between the bottom of the top plate of the table and the top of the frame below said plate, which recess provides a substantial contrast between frame and the top plate of the table.

I claim:

The ornamental design for a table or similar article, substantially as shown and described.
